UNITED STATES PATENT OFFICE

101,740

DESIGN FOR A SWIVEL MOUNTED AIR-CIRCULATING DEVICE

Benjamin Kirsch, Chicago, Ill., assignor to Auto Radiator Mfg. Co., Chicago, Ill., a corporation of Illinois

Application June 25, 1936, Serial No. 63,486

Term of patent 7 years

To all whom it may concern:

Be it known that I, Benjamin Kirsch, a citizen of the United States and a resident of Chicago, Cook County, Illinois, have invented a new, original, and ornamental Design for a Swivel Mounted Air-Circulating Device, of which the following is a specification, reference being had to the accompanying drawing, forming part thereof, in which Fig. 1 is a top plan view of a swivel mounted air-circulating device showing my new design;

Fig. 2 is a side elevation of Fig. 1 showing a swivel mounted air-circulating device; and

Fig. 3 is a bottom plan view of Figs. 1 and 2 showing a swivel mounted air-circulating device.

I claim:

The ornamental design for a swivel mounted air-circulating device, substantially as shown.

BENJAMIN KIRSCH.
